MOLDED SHROUD FOR PLUG CONNECTOR

Kenneth Norman Karol, Harrisburg, Pa., assignor to
AMP Incorporated, Harrisburg, Pa.

Filed Oct. 15, 1965, Ser. No. 87,514

Term of patent 14 years

(Cl. D26—1)

FIGURE 1 is a perspective view of a molded shroud for a plug connector showing my new design;

FIGURE 2 is a side elevational view of the device shown in FIGURE 1; and

FIGURE 3 is a front elevational view thereof.

The broken-line showing of a plug tip and lead wire in FIGURE 1 is for illustrative purposes only.

I claim:

The ornamental design for a molded shroud for plug connector, as shown and described.
